Primary Examiner—Nelson C. Holtje*Assistant Examiner*—M. N. Pandozzi*Attorney, Agent, or Firm*—William J. Ruano[57] **CLAIM**

The ornamental design for a stadium simulating transparent bowl, as shown and described.

DESCRIPTION

FIG. 1 is a top view of a stadium simulating bowl showing my new design;

FIG. 2 is a side view thereof;

FIG. 3 is a bottom view thereof; and,

FIG. 4 is a vertical sectional view thereof taken along line 4—4 of FIG. 1.

The broken line showing of an illustrative label in FIGS. 1—4 is for environmental purposes only and forms no part of the claimed design. The slanted lines indicate transparency.
